(57) **CLAIM**

The ornamental design for a LED projector light, as shown and described.

DESCRIPTION

FIG. 1 is a back-right perspective view of a LED projector light.

FIG. 2 is a right elevation view of the LED projector light.

FIG. 3 is a left elevation view of the LED projector light.

FIG. 4 is a front elevation view of the LED projector light.

FIG. 5 is a back elevation view of the LED projector light.

FIG. 6 is a top elevation view of the LED projector light; and,

FIG. 7 is a bottom elevation view of the LED projector light. The broken lines showing in the drawings are for the purpose of illustrating portions of the LED projector light and form no part of the claimed design.
